UNITED STATES PATENT OFFICE.

ARTHUR E. TROIEL, OF OAKLAND, CALIFORNIA.

SYSTEM OF CONCRETE CONSTRUCTION.

Application filed December 9, 1920, Serial No. 429,346. Renewed August 16, 1926.

This invention relates to an improved system of concrete wall construction and the forms for carrying the same into practice.

The principal object of my present invention is to provide a system of interchangeable forms for hollow concrete walls which contain dead air spaces to prevent the transmission of moisture from the outside of the building to the inside of the same.

10 In constructing a hollow wall of this character I provide a system of forms which are vertically movable on stationary corner pieces. I provide an improved form of tie rod by which the forms are temporarily held in spaced relation while the concrete is being poured, and after the latter has set, a portion of the said tie rods are removed in order that the forms may reset in a vertical direction. Another portion of the tie rod remains

15 embedded in the inner and outer wall sections to effectively tie them together.

I also provide forms which enable me to form recesses in the wall for sliding windows, the forms for the latter being expandable so that after the pocket is formed they may be again expanded to contact with the adjacent core forms and thus, above the window pocket, make a continuous air chamber.

20 My forms are so constructed that a maximum degree of rigidity is secured so as to avoid the use of stays and other similar devices for holding the forms in a vertical position. By the use of a comparatively small number of form sections, a wall length of almost any dimension may be constructed. In connection with these forms there is also provided means by which girders and cornices may be integrally formed with the walls and floors. I also provide means which

25 enables a gable to be constructed with the use of only one special form for this purpose.

With these and other objects in view, my 30 invention consists in certain novel features of construction, combinations and arrangement of parts herein illustrated and more particularly pointed out in the appended claims.

35 Reference being had to the accompanying drawings forming a part of this specification:

Figure 1 is a view in plan of a building structure showing the manner in which the 40 several members of my form are used.

Figure 2 is a view in section through the base of a concrete wall showing the manner in which the footing may be formed.

Figure 3 is a view in section of a side wall showing the side plates, the core form and 45 the jack for raising the parts.

Figure 4 is a view in side elevation of a core form.

Figure 5 is a view in section showing the use of my form parts for moulding a cornice. 50

Figure 6 is a view in perspective of the standard side plate.

Figure 7 is a view in perspective of an inside corner plate.

Figure 8 is a view in perspective of an 55 angle form plate.

Figure 9 is a view in side elevation of the T iron which is attached to the corner forms and on which the intermediate side forms are slidable.

Figures 10 and 11 are views in plan and side elevation showing details of the connection between corner form plates and side form plates.

Figure 12 is a view in plan of the tie bar 60 which constitutes a part of the arrangement for holding the form plates in position.

Figure 13 is a view in perspective of a mold section which is used for stopping off the air spaces and for other purposes.

Figure 14 is a view in plan showing the use of a modified form of side plate.

Figure 15 is a view in end elevation showing the use of the hinged gable plates.

Figure 16 is a fragmentary sectional view 70 through one end of a core form.

Figure 17 is a view in side elevation showing a portion of the forms for a building preparatory to pouring the concrete.

Referring to corresponding parts in the 75 several views by the same numerals and letters of reference, my forms comprise a number of types which I have designated by A to G inclusive. Type A which is used on inside corners comprises the sides 1 and 2 formed generally at right angles to each other. Along the side edges are bent flanges 3, the outer ends of which are ribbed as shown at 4. The flanges 3 are provided with a row of uniformly spaced holes 7 which enables the member to be attached to other form sections or to the guide bars hereinafter described. These corner members are made preferably in lengths which correspond to the height of the walls and are 80

105

110

- carefully aligned and held in a vertical position. The guides 6 above referred to may be formed of T-bars which also serve to connect two or more corner sections together. 5 These bars have holes 8 drilled through the web into the stem and this opening is screw threaded for suitable connecting bolts 9. The holes 8 are spaced apart a multiple of the spacing of holes 7.
- 10 The outside corners and flat wall surfaces are formed by type B plates particularly illustrated in Figure 6. These plates comprise the flat portions 10 having flanged ends 11 which in turn are ribbed as shown at 12. 15 The flanges have uniformly spaced holes 13, the spacing corresponding to that in the flanges of the corner sections. The ends of these flanges are notched and grooved as shown at 14 for engagement with the guides 6. To prevent buckling of the type B plates in a direction at right angles to the flanges I rivet angles 15 to the sides and if required one or more intermediate angles 16. In addition I rivet flat plates 17 inside of the 20 flange ends which plates are slotted to match slot 14. When the plates 10 are adjacent a corner form it is necessary to prevent them from pulling apart and for this purpose I provide a bar 18 which is bolted to the rib 12 and provided with a hooked end 19 which engages the rib of the adjacent corner member. The type A and B sections also have 25 rows of uniformly spaced holes 20. Throughout this specification and claims the parts having cooperating holes therein have been defined as having equally spaced holes, uniformly spaced holes, etc., and it should be understood that such expressions are intended to include a series of holes which are spaced multiple distances relative to a cooperating series of holes.
- 30 The outside corners are formed by bolting together two of the type B sections, the flange of one being placed against the inside face of the other and bolts passed through holes 13 and 20. Type C plates are used for 35 making an angular offset in the wall or for forming fillets between a vertical and a horizontal surface. These plates comprise the flat body 22 with the angularly bent flanges 23. The body and flanges are provided with holes 24 and 25 spaced the same as the corresponding holes in the type A and B plates. These plates are used as shown in Figures 2 and 5. At 26 in Figure 2 one of the type C sections is bolted to the face of a type B section by passing bolts through a hole 20 in each row and then through the holes 25. This enables the thickness of the toe of the 40 footing to be varied by the spacing of the holes 20. The upper flange of the angle plate is bolted to the lower flange of a type B plate. The B and C plates may also be connected by the use of angles 28.
- 45 The core forms comprise a non-expansible

type denoted by D and an expandable type denoted by E. The former comprises side plates 30 which have their upper edges crimped to engage two back-to-back channel members 31. These channel members are 50 bolted between two opposed plates 30 and their upper flanges are engaged by the lifting jack later described. The channel members have a height equal to the width between the side plates and short lengths of 55 the channels are attached to the ends of the plates 30 and thus close these ends. In the type D cores an end channel 32 is placed in each end of the core leaving open the bottom only. 60

Where the type E core form is used two side plates 30 are placed one against the other and then bolted to channels. This is the equivalent of one part of the form telescoping in the other, and of course one end 65 only of each part is closed by an end channel 32. The side plates in both types are formed with slots 33 extending upwardly from their lower edges. These slots are to 70 permit the entrance of the tie bars next described.

The tie device comprises a flat bar 34 having bent ends 35 which are provided with screw threaded openings 36. The side edges of the bar are notched as shown at 37 for 75 engagement by the edges of slots 33. The distance between the bottom of opposed notches is the same as the width of slots 33. Thus when the slots of the plates are engaged in the notches of a bar 34 the 80 latter holds the lower edges of the plates in 85 spaced relation.

Engaged in holes 36 are screws 37 which are provided with substantially rectangular 90 eyes 38. This shape is used so that the eye 105 will rest flat against the outside of the form plates. In construction, the bars are placed in slots 33 above the finished concrete as 110 shown in Figure 2 and the screws 37 entered through holes 20 in the side plates and engaged in the holes 36. When the screw heads are tightened against the faces of the plates 10, the latter will be effectively clamped 115 against the finished work. These ties may also be used to hold the reinforcing rods in 120 position two of these rods being indicated at 40 in Figure 3. After the space between the core and the outside plates have been filled with concrete the screws are removed, the bar remaining in position to tie the wall sections together.

The lifting of the form sections is accomplished with jacks as illustrated in Figures 3 and 4 and any number of which may be used along the upper edge of the construction. Each jack comprises the two-legged stands 41 across the tops of which is fastened a bar 42. In threaded engagement with this bar is a screw 43 having a hand 125 operating wheel 44. A clutch disk 45 is 130

The core forms comprise a non-expansible

swiveled to the lower end of the screw and this disk is slotted to engage the upper flanges of channels 31. Attached to the channels by bolts 46 extending through the 5 core plates as well, are laterally extending arms 47 the outer ends of which are bolted to the flanges of the side plates 10. These arms thus serve to hold the upper edges of the side plates in spaced relation to the core 10 and each other. In addition the side plates are tied to the core so that when the latter is raised by the jack, the side plates are also raised.

To form a cornice or overhang I attach 15 one of the B type plates in a horizontal position by resting one of its ribs on the flange of a lower side plate as shown in Figure 5. Then a moulding form of the desired shape 20 as shown at 50 is bolted to the holes 20 in the horizontal plate. The outer edge of the latter may be supported in any desired means such as a brace 51. The upper ends of the air spaces are stopped off after the 25 core is removed by placing a cap 52 of metal or other material across the opening before the final pouring of concrete is made.

The section shown in Figure 13 and designated as type F is used for various purposes 30 and is made in different widths. This type of form has a channel shape with the web 53 provided with a longitudinal centrally disposed row of holes 55. The flanges 54 have holes 56 which are spaced the same as holes 7 and 13 as these flanges are frequently 35 bolted to type A or B forms as shown at 57 and 58 respectively in Figure 1. These sections are also bolted between vertical side wall and core sections to stop off the concrete where wall openings are formed.

40 These forms are also used to connect the tops of the corner forms and also as guides for the vertical reinforcing steel. This use is shown in Figures 1 and 17. Several of the sections are connected endwise and bolted 45 between opposite corner sections at their upper ends. The reinforcing steel 60 may then be slipped through the holes 55 as guides. These sections thus hold the corner 50 guide forms from spreading and the steel in the center of the wall sections. After the pouring of the concrete has proceeded to a sufficient height these type F sections are removed, as at that time the tie members will effectively hold the corners and the stiffness 55 of the steel will keep it in place.

The modified side plate shown in Figure 60 14 and denoted by G is constructed the same as the B sections except that one edge is not flanged. This plate is used only in connection with one of the corner forms where a close adjustment of wall length is desired. By bolting one of this type of sections to the 65 regular corner form a variation may be made in length of wall as the spacing of holes 20. These plates may also be provided with spe-

cial punchings which enable them to be used to finish gable walls. In this case two of the plates denoted by 61 are pivoted together near one corner as shown at 62. A number of holes 63 are punched on an arc the center 70 of which is that of the pivot 62. The spacing of these holes is such that all the regular roof pitches may be obtained by merely bolting the two plates together through certain designated holes. These gable plates may 75 be used by bolting to the regular corner and side plates as shown in Figure 15, or the gable may be built up in step fashion by the B plates and after they have been removed the gable plates clamped in position and the 80 upper edges finished.

In use the corner members A and the plates B which are used at the corners are made in lengths of say ten feet. The inside and outside corners are placed in position 85 and securely anchored. The forms may be held square by means of the corner bars 65. Where long stretches of flat wall surfaces are to be formed several of the type B plates may be joined together as shown at 66. 90 Only a single row of B sections is used between opposite corner guides, these sections and the cores being raised vertically as the work proceeds.

One use of the expandible core forms is 95 shown in Figure 1 where a window opening 67 is provided with side pockets 68. These pockets are closed from the air space between the walls by bridges 69. After the top of the opening has been reached the forms are 100 expanded a sufficient distance so that the ends meet the adjacent core forms.

Where form sections such as C or the moulding 50 are used the proper corners are 105 of course provided. In making up the cores the same channels are used both for the ends 32 and between the plates as at 31, hence the latter only appear at intervals depending on the spacing of the lifting jacks.

I claim as new and wish to cover by Letters Patent:

1. A system of forms for plastic wall construction consisting of two relatively spaced vertically extending pairs of corner forming sections, each pair comprising a self-sustaining rigid and unitary inner angular metal plate member and a complementary outer angular member spaced therefrom, inner and outer wall sections between and supported for vertical adjustment on the inner and outer corner sections respectively, and means for holding the inner and outer wall sections together to move simultaneously while in spaced relation to each other and without movement of the corner sections.

2. A system of forms for plastic wall construction consisting of two relatively spaced vertically extending pairs of corner forming sections, each pair comprising a self-sustain-

ing rigid and unitary inner angular metal plate member and a complementary outer angular member spaced therefrom, and relatively narrow side wall forming sections supported by and vertically adjustable on said corner sections as the wall construction proceeds.

3. A system of forms for plastic wall construction comprising vertically extending inner and outer angular corner forming sections, vertical guides carried by and along the edges of the said corner sections, relatively narrow side wall forming sections extending between said corner sections, and means on the ends of the side sections for engaging and forming a vertically movable tongue and groove connection with said guides.

4. A system of forms for plastic wall construction comprising spaced inner and outer corner forming forms, flanged edges on said forms, guides removably attached to said flanges, side wall sections extending between said corner sections, and means on the ends of said side wall forms for engaging said guides and providing a tongue and groove connection permitting a vertical movement thereon as the wall construction proceeds.

5. A system of forms for plastic wall construction consisting of two relatively spaced vertically extending pairs of corner forming sections, each pair comprising a self-sustaining rigid and unitary inner angular metal plate member and a complementary outer angular member spaced therefrom, inner and outer wall sections between and supported for vertical adjustment on the inner and outer corner sections respectively, and inter-locking guide means cooperating with the wall sections and corner sections for preventing the lateral separation of such sections while permitting the wall sections to be moved vertically on the corner sections.

6. A system of forms for concrete wall construction comprising an inner corner section, an outside corner section said corner sections extending to the height of the finished wall, inside and outside wall sections vertically movable on said corner sections, core forms between said side wall sections to form an air chamber in the wall, and means for holding the upper and lower edges of said core forms in spaced relation to said side sections, the means for holding the said lower edges being detachable and adapted to remain in the formed wall when the forms are removed.

7. A system of forms for concrete wall construction comprising an inner corner section, an outside corner section said corner sections extending to the height of the finished wall, inside and outside wall sections vertically movable on said corner sections, core forms between said side wall sections

to form an air chamber in the wall, means above the moulded wall for holding the upper edges of said core forms and said side sections in spaced relation and tie rods adjacent the lower edges of said core forms, for holding said forms in spaced relation between the side sections, said tie rods being adapted to be embedded in the wall to tie the parts together.

8. A system of forms for plastic wall construction comprising side wall sections, core forms for forming an air chamber within the wall, means for holding the top edges of the core forms in spaced relation with the side wall sections said core forms having vertical open ended slots in the lower edges thereof, tie rods extending across said air chamber to become permanently incorporated in the wall sections and having notches on the edges thereof adapted to be engaged by the edges of said slots, and removable screw members extending through said side sections and engaging opposite ends of said tie rods.

9. A form for plastic walls comprising sections having contact faces, angular flanges along the longitudinal edges of said sections having uniformly spaced holes therein, the faces of said sections having a plurality of transverse rows of holes spaced equally with those in the flanges, and transverse stiffening ribs extending across the back of said sections.

10. A form plate for plastic wall construction comprising contact surfaces, angular flanges along the edges thereof, ribs on the outer edges of said flanges, said contact surfaces and said flanges having openings spaced so that the flanges may be interchangeably fastened together or the flange of one section plate may be fastened to the contact surface of another.

11. A form section for plastic wall construction comprising two plates at right angles, flanges along the non-adjacent side edges of said plates and guide members removably attached to said flanges.

12. In a form construction for plastic walls comprising corner sections, guides along the vertical edges of said corner sections, side wall sections movable on said guides, tie members extending between opposed corner sections, said tie members having a plurality of closely spaced openings adapted to serve as guides for the vertical wall reinforcing.

13. In a form construction for plastic wall construction comprising corner sections, vertically movable side wall sections, channel-shaped tie members extending between opposed corner sections, said tie members having spaced openings adapted to act as guides for wall reinforcing material.

14. A core form for plastic wall construction comprising side plates, offset upper edges formed thereon for holding said plates

in spaced relation and means clamped between said offset edges for engaging lifting means.

15. A core form for plastic wall construction comprising side plates, offset bends on the upper edges of said plates, said offset bends contacting at the center of the form, channel shaped plates forming a closure for the ends of said form, and opposed channel plates clamped between the said offset bends for engagement with lifting means.

16. A core form for hollow plastic walls comprising overlapping side plates having slots on their lower ends, channel members forming a closure for the ends of said form, offset bends along the top edges of said side plates and opposed channel members clamped between the said offset bends.

17. A wall form for plastic wall construction comprising flat plates, flanges along one of the edges of said plates, means pivotally connecting said plates adjacent one cor-

ner and said plates having openings on an arc about said pivot, said openings serving as a gauge for fastening said plates at an 25 angle to each other.

18. A system of forms for plastic wall construction consisting of two relatively spaced vertically extending pairs of corner forming sections, each pair comprising a 30 self-sustaining rigid and unitary inner angular metal plate member and a complementary outer angular member spaced therefrom, inner and outer wall sections between and engaging the inner and outer corner sections and vertically movable thereon respectively, and means at their engaging points for detachably and adjustably holding the corner and wall sections together with the wall sections supported on the cor- 35 40

In testimony whereof I affix my signature.

ARTHUR E. TROIEL.
